ATTORNEY

UNITED STATES PATENT OFFICE.

ROY R. HERRICK, OF JACKSON, MICHIGAN.

TOBACCO-CAN.

1,285,168.

Specification of Letters Patent. Patented Nov. 19, 1918.

Application filed August 28, 1917. Serial No. 188,642.

To all whom it may concern:

Be it known that I, ROY R. HERRICK, a citizen of the United States, residing at Jackson, in the county of Jackson and State 5 of Michigan, have invented certain new and useful Improvements in Tobacco-Cans, of which the following is a specification.

This invention relates to new and useful improvements in tobacco cans and the like, 10 and the principal object of the invention is to provide a device of this nature with means whereby the contents will always occupy a position at the top of the can.

Another object of the invention is to provide a movable bottom in the can so the 15 same can be moved out as the contents are removed to keep the remaining tobacco near the top of the can.

Another object of the invention is to provide spring means for holding the movable 20 bottom of the can in place.

Another object of the invention is to provide a device of this character which is simple and durable in construction, reliable and 25 efficient in operation and one which can be manufactured and placed upon the market at a minimum cost.

The invention also consists in certain 30 other features of construction and in the combination and arrangement of the several parts to be hereinafter more fully described, illustrated in the accompanying drawing and specifically pointed out in the appended 35 claims.

In describing my invention in detail, reference will be had to the accompanying drawings, wherein like characters denote like or corresponding parts throughout the 40 several views and in which:

Figure 1 is an elevation partly in section,

Fig. 2 is a longitudinal sectional view,

Fig. 3 is a section on line 3—3 of Fig. 2,

Fig. 4 is a section on line 4—4 of Fig. 2.

In these figures, 1 indicates the can of any desired shape, that shown being of the ordinary flat shape and having a top 2 hinged at 3 to the body of the can. At the bottom 45 the can is left open and in this open end I place the movable body 4 which is provided with side flanges 5 to afford a support for the bottom against the long sides of the can and to strengthen said bottom. 6 indicates a spring plate secured to the under 50 side of the bottom by means of the plate 7

secured to the bottom by the rivets 8. The spring plate 6 extends beyond each end of the bottom and has its ends rounded and engaging with corrugations 9 formed on each of the narrow sides of the can. These corrugations may be formed in the can itself or they may be formed on the strip 10 and this strip secured on each end of the can as shown in the drawings. The can is 60 provided with a slot 11 at its upper end and the strip 10 has its end turned over and secured to the edge of this slot, the slot being covered by the top when the can is closed. At its lower end the strip 10 is gripped by 65 the turned-up lower edge 12 of the bottom of the can. 70

When the contents of the can are partly used and it is difficult to extract them from the can, by inserting the fingers under the 75 bottom and pushing the same upwardly the contents are moved close to the top of the can so that it can be readily removed therefrom.

While the drawings show a space between 80 the movable bottom and the sides of the can, it will be understood that this is so shown to better illustrate the invention, as in actual practice said bottom is made to snugly fit the can so as to prevent leakage 85 of the contents thereof and to prevent the passage of air thereto.

It is thought from the foregoing that the 90 advantages and novel features of my invention will be readily apparent.

I desire it to be understood that I may make slight changes in the construction and in the arrangement and combination of the several parts, provided that such changes 95 fall within the scope of the appended claims.

What I claim is:—

1. A tobacco can having its bottom open and the edges thereof turned up to provide pockets, said can having an opening in each 100 side adjacent the top thereof, a corrugated strip secured to each side of said can by passing and bending their upper ends through said openings and gripping their lower ends in said pockets, a movable bottom in said can, and means thereon for engaging with the corrugations in the strips for adjustably mounting said movable bottom in the can. 105

2. A tobacco can having corrugations 110 along its opposite narrow sides, a movable plate in said can, side flanges bent from

said plate to engage the wide sides of the spring plate and movable plate adjacent the ends of the metal for securing the spring plate to the movable plate. In testimony whereof I affix my signature in presence of two witnesses.

5 engagement with the corrugations, a piece of metal covering said spring plate to extend longitudinally thereof, and terminating adjacent the ends of the movable plate to limit the flex of the ends of the spring 10 plate, and rivets passing through the metal,

ROY R. HERRICK.

Witnesses:

Mrs. R. R. HERRICK,
Wm. H. HANKINS.
